UNITED STATES PATENT OFFICE.

JOHN GRAHAM, OF CHICAGO, ILLINOIS.

DESIGN FOR A FONT OF COMBINATION TYPE ORNAMENTS.

SPECIFICATION forming part of Design No. 18,946, dated March 5, 1889.

Application filed January 5, 1889. Serial No. 295,571. Term of patent 3½ years.

To all whom it may concern:

Be it known that I, JOHN GRAHAM, a citizen of the United States of America, residing at Chicago, in the county of Cook and State 5 Illinois, have invented a certain new and useful Design for a Font of Typographical Combination Ornaments, of which the following is a specification, reference being had therein to the accompanying drawing.

10 My invention relates to a design for a font of typographical combination ornaments, consisting of separate type ornaments of waved, curved, and scrolled lines, and angular lines, and straight transverse lines, all of said ornaments being capable of unitary combinations, 15 as described and shown.

The characters 2 to 7, inclusive, consist of three curved, waved, and mostly heavy lines, all the lines running in substantially the 20 same direction.

Ornaments 8 to 16, inclusive, 23 and 28, consist of light curved and scrolled lines.

Ornaments 17 and 19 are alike, being reversed in position, and consist of curved 25 scrolled lines and ornamental sprays. The outline of 18 consists of numerous semicircles surrounding a central fine-pointed star.

Ornaments 20 and 21 are alike, being reversed in position.

30 22 consists of two dark transverse lines intersecting each other at the middle at right angles, and four groups, each composed of four light straight parallel lines, two of the groups being parallel with each other and 35 with one of the dark lines (the dark lines being located centrally between the groups) and transverse to the other two groups and dark line. The fine lines composing each of the said groups are placed so closely together 40 as to produce a shaded appearance, as shown in the printed illustrations.

Ornament 24 consists of a large dark circular center and fine waved curved radial lines, and 25 consists of a comparatively small dark center and heavy curved radial lines. 45

Ornaments 26 and 27 are alike, being reversed in position, and consist of fine curved scrolled lines terminating in dark dots.

29 and 30, inclusive, are adapted for corner ornaments of border lines. 50

Characters 31 to 39, inclusive, consist of four light curved and waved lines.

40 and 41 consist of lines curved and connected so as to form numerous small oval spaces, constituting a variegated and spotted 55 ornament.

42 and 43 consist of angular lines connected so as to form angular spaces of different shapes and sizes, and these characters are capable of being joined together at many different points, as shown. 60

Characters 44 to 48 consist of three light curved and waved lines, and 49 to 52, inclusive, consist of four heavy shaded curved and waved lines. 65

The ornament 53, peculiarly shaped as shown, is adapted to be combined with the other ornaments and characters of the font, as shown in the printed illustrations. 75

What I claim as new is— 70

The new design for a font of combination type ornaments, consisting of waved, curved, scrolled, and angular lines and of straight parallel and transverse lines, all as shown and as herein described.

In testimony whereof I affix my signature in presence of two witnesses.

JOHN GRAHAM.
